PROPELLER SPINNER

Henry G. Junger, Dumont, N. J., assignor to Air
Associates Incorporated, Bendix, N. J., a cor-
poration of New York

Application January 1, 1942, Serial No. 425,254

3 Claims. (Cl. 170—159)

The present invention relates to a spinner for an aircraft propeller. In spinners of the type hereunder consideration, it is imperative that the entire outer surface is evenly curved and that no projections or other interruptions of its smooth skin disturb the uniform flow of the air current along the surface in flight. For this reason, the means for securing the spinner of conventional type to a propeller hub are arranged in its interior with the effect that these means are accessible only from the rear of the propeller. In consequence thereof, particularly in constant speed-full feathering propellers which require frequent inspection of the control mechanism arranged in front of the hub, it is a cumbersome and time wasting job to remove and to restore the spinner for that purpose because of the limited space in the rear of the propeller and of the necessity of removing other parts, such as the motor cowl, in order to provide access to the parts inclosed by the front portion of the spinner.

The invention contemplates the provision of a spinner whose front part at least can be removed from or attached to the propeller hub from the front side without sacrificing the smoothness of the surface or any other required quality of an efficient spinner. The invention further aims to provide a spinner of the mentioned type whose central front portion is free from impeding interior structure so as to be useful to encase an extraneous propeller control mechanism or other device. The invention consists of a spinner comprising a bipartite shell, the rear part of which can be slipped over and secured to the hub from the rear; whereas the front part can be secured to or removed from the other part by working from the front side. The invention further comprises the provision of a trap door mechanism for openings in the front removable shell through which tools may be applied to the means connecting the two parts to each other. The invention also comprises a removable partition or bulkhead stiffening the front end of the rear shell and holding it concentric with the propeller hub center line.

Further details and objects of the invention will be apparent from the description given herein-after and the accompanying drawings illustrating an embodiment thereof by way of invention.

In the drawings:

Fig. 1 is a longitudinal section of a spinner according to my invention;

Fig. 2 is a rear elevation thereof, parts of the shells being broken away;

Fig. 3 is a sectional view of a portion of the

spinner showing the connection of the bulkhead to the rear shell on a larger scale;

Fig. 4 is a similar view of the connection of the two shell parts and of a trap door;

Fig. 5 is a top plan view of the trap door of Fig. 4;

Fig. 6 is a section along line 6—6 of Fig. 5;

Fig. 7 shows a modification of the parts illustrated in Fig. 4, and

Fig. 8 shows a cross-section along lines 8—8 in Fig. 7.

Referring now to the figures, 10 indicates a propeller hub to which a spinner according to my invention may be applied, and 11 denotes a diagrammatically illustrated controlling mechanism for the blade adjustment, which mechanism is attached to the front of the hub 10. A rear flange 12 and a front flange 13 are integral parts of the propeller hub. The spinner comprises a front shell 14 and a rear shell 15 of sheet metal, e. g. an aluminum alloy, so shaped as to form the front portion of a substantially streamlined body whose rear portion may be constituted by an adjacent part (not shown) of an airplane to which the spinner may be applied. Means are provided to stiffen this shell and to attach it to the propeller hub 10 when slipped over the latter from the rear. For this purpose, the shell 15 has a bottom 16 with a peripheral flange 16' fitting into the shell 15 and secured thereto by means which do not cause a projection on the outer surface, e. g. by spot-welding or flush-riveting. Bottom 16 has a central opening 17 and a number of bolt holes 18 in registry with corresponding holes in flange 12 for the attachment of the bottom 16 thereto by means of the bolts and nuts 19. The front end of the shell 15 is circumferentially set off or restricted at 20 and bent inward so as to form a flange 21.

In order to permit shell 15 to be slipped over the hub 10, recesses 40 are provided, as many as there are propeller blades 41, i. e. three in the illustrated embodiment. The recesses extend from the front end of the shell and are so shaped

that the blades 41 can pass therethrough as far as required for the attachment of bottom 16 to flange 12. A stiffener 42 of angular cross-section is secured all along the rim of each recess on the inside of the shell by means indicated at 43. The front ends 44 of the stiffener are bent off parallel to the flange 21 and secured thereto in combination with other parts as will be explained herein-after. The portion of each recess 40 not occupied by the pertaining blade when the spinner is attached to the hub can be closed by a lid 45

55

having lateral flanges 46 fitting between the inward directed legs 47 of the stiffener 42. Flanges 46 are secured to the legs 47 by means of the bolts 48.

A mounting ring 22 of angular cross-section and considerably smaller outer diameter than the inner diameter of the shell in the same plane is provided with holes 23 in registry with similar holes in flange 13 so that the ring 22 can be secured to the hub flange 13 by means of bolts 24 with nuts 25. The ring 22 has a cylindrical rim 26 whose outer surface constitutes the seat for slidable engagement of the bulkhead 27 which will be described hereinafter. However, it will be clear that ring 22 is a unit separate from hub 10 only for reasons of manufacture and that for the purpose of the present invention the cylindrical face provided by the ring portion 26 may be a face of the hub proper. The bulkhead 27 of the illustrated embodiment comprises a sheet metal body having a main portion 28 of conical shape, a plane outer flange 29, a cylindrical inner end 30, and a lining 37 of an elastic material, such as synthetic rubber, secured to the inner surface of the cylindrical end 30 by any suitable means such as rivets 37'. The dimensions are so selected that the bulkhead can be shifted in axial direction from the front side of the hub on the cylindrical portion 26 of mounting ring 22 whereby the elastic lining will be somewhat compressed. In assembled position flange 29 of the bulkhead is in front of and slightly spaced from the flange 21 of shell 15 as clearly shown in Fig. 1. Instead of being secured to the bulkhead the lining 37 may be fastened to the outer surface of the ring 22. However, the illustrated arrangement is preferred because it is easier in production to make the mounting ring fit the hub and the bulkhead than to make the bulkhead fit the mounting ring.

The rear end of the front shell 14 is provided with an internal flange 31 of L-shaped cross-section whose outer substantially conical portion 32 fitting the shell curvature is secured to the inside of the front shell 14 by suitable means such as spot-welding or flush-riveting (not shown); whereas the substantially plane portion 33 in the assembled spinner is located in front of and slightly spaced from the bulkhead flange 29. The rear end of front shell 14 with the portion 32 of flange 31 fits over the restricted end at 29 of the rear shell 15, and the parts are so shaped that the outer surface of the rear shell is the uninterrupted continuation of the outer surface of the front shell 14 except for the insignificant gap 34 which may occur where the two parts meet. The front end of the shell 14 may be provided with a central hole 35 closed by a removable cap 36 which is shown as made of rubber but may be made of any suitable material. It will be noticed that the bulkhead 27 intermediate the two shells is funnel shaped rather than plane. This has been done in order to give this part greater stiffness and also to make the front shell shorter, i. e. to make both shells more similar to each other in length than it would be possible with a plane bulkhead. The connection of the bulkhead to the rear shell 15 and of the front shell to the rear shell in the illustrated embodiment is accomplished in the following manner. It has been stated hereinbefore that the end flanges 44 of the stiffeners 42 are secured to the rear side of the shell flange 21; thereby six local reinforcements of the flange 21 are produced. These reinforced portions are utilized to anchor a stud

bolt 50 in each of them as is clearly shown in Fig. 3. Each bolt has a flange head 51 and is passed from the rear side through a hole 52 in the reinforced portion. The head 51 is secured to that portion by rivets 53 or other suitable means. The rear portion of the shaft of the stud bolt is provided with longitudinal edges 54 forced into the wall of the hole 52 thereby contributing to the resistance of the bolt against undesired turning. The front end of the bolt is threaded at 55 so as to receive thereon a nut 56 bearing on the front end of a flanged tubular steel piece or ferrule 57 whose other end is flared into the rear face of a steel ring or washer 58 which is assembled on the rear side of 29, and the piece 57 is passed through a corresponding hole in flange 29 against whose front face piece 57 bears with its flange. A hole 60 is also provided in flange 33 in registry with the holes 52 and 59 and of sufficient size to permit the nut 56 to pass therethrough with ample clearance. In the illustrated embodiment six such bolts 50 are provided in accordance with the number of reinforcing ends of the stiffeners 42. However, it will be clear that no immediate connection need exist between the stiffeners and the bolt, and that any other suitable number of bolts may be used because it is necessary only to anchor the bolts to the flange 21 and to secure thereto the bulkhead 27 when applied to the bolts from the front end of the shell 15.

In a similar manner a second set of anchor stud bolts 61 shown in Fig. 4 is used to secure the flange 33 of the front shell to the bulkhead flange 29 and the rear shell flange 21. Each stud bolt 61 has a head 62 secured to the rear side of flange 21. A ferrule 63 is provided whose flange safeguards the desired spacing of flange 29 from 21; whereas another ferrule 64 of a shape similar to that of the afore-mentioned ferrule 57 fittingly engages a hole 65 in flange 33. The pieces 63 and 64 abut against each other and a gasket ring or washer 66 is provided between flanges 29 and 33. Now it will be clear that nuts 67 on bolts 61 which are passed through the ferrules 63 and 64 will hold the front shell securely attached to the bulkhead and the rear shell 15. In the illustrated embodiment the set of bolts 61 is so arranged that circumferentially one bolt 61 follows two bolts 50. However, it will be understood that other arrangements may be used in an equally satisfying manner. It is even possible to use only bolts 61 and connections of the type illustrated in Fig. 4 because it is only necessary according to the spirit of the invention to secure the parts in consideration to each other from the front side of the propeller to which the spinner is applied.

In order to make the nuts 67 of the set of bolts 61 accessible from the front of the propeller hub I provide trap doors in shell 14, one in front of each of the bolts so that a tool such as a wrench may be applied through the door opening for removing or fastening the nuts. Each trap door device 70 comprises a reinforcing plate 71 secured to the inner surface of shell 14 and having an opening 72 in registry with an opening of like size and shape in the shell proper. The opening 70 is elongated according to the inclination of the portion of the shell curvature with respect to the axis of the pertaining bolt 61 so that a tool 73 indicated by dash lines in Fig. 4 may be passed through the opening and stuck on the nut 67. The front end of plate 71 is formed as the sta-

tionary part 75 of a hinge. The trap door proper consists of a plate 76 with the movable hinge part 77 and upturned rims 78 and 79 on both longitudinal sides. A pivot rod 80 is passed through hinge parts 75 and 77. A filler 81 of the size of the opening 72 is riveted at 82 to the bottom of the trap door so that the surface of the spinner is uninterrupted when the trap doors are closed. It will be clear that a trap door of the type disclosed will always be closed owing to the centrifugal force when the spinner is rotating, and that it can be opened by pressure exerted from the outside against the filler 81. In order to ensure closing of the trap door even if the spinner is standing still a spring 83 is wound about the pivot rod 80 at 84 and bears with a loop portion 85 against the top of the plate 76. The ends 86 and 87 of the spring 83 are held by a retainer 88 which is secured to the inside of the shell 14. Detent means are provided to hold the trap door open against the restraint of spring 83 while a tool such as 73 is applied to the pertaining nut 67. For this purpose, a portion of plate 71 is bent inwardly and upwardly inclined so as to form a tab-like projection 90, and a leaf spring 91 is secured thereto at 92 as clearly shown in Fig. 6. Trap door plate 76 has also a lateral extension 93 bent upward and provided with a sideway projecting upper rim 94. The extension 93 is formed substantially triangular as best seen in Fig. 4 so that when the trap door is lifted rim 94 will come to rest on top of the end 95 of leaf spring 91 whereby the trap door is prevented from being shut. By reaching with a finger through the opening 72 one is able to push back the spring 91 whereupon the trap door will be shut by spring 83.

It will be seen that the minimum size of the trap door opening is so defined that its projection upon a plane perpendicular to the axis of the coordinate bolt is at least equal to the cross-section of the tool applied to the nut 67. In consequence thereof, it may happen in certain spinners where the curvature of the shell in an axial plane is very shallow that trap doors of very considerable size and tools of excessive length are required if the axes of the bolts 61 are parallel to the spinner axis. This difficulty can be overcome by a structure according to the modification shown in Figs. 7 and 8. In this structure the axis 100 of bolt 61 is inclined and it will be clear that such inclination of axis 100 diverging as to its forward directed portion from the spinner axis (not shown) brings the trap door mechanism—only part of which is shown in the figure—closer to the connected flanges and simultaneously permits a trap door of smaller size than would be necessary if the axis 100 were parallel to the spinner axis. However, it will be likewise clear that the inclination of the bolt axis also calls for an inclination of the flange 121 of the rear shell 115, of flange 129 of bulkhead 127, and of flange 133 of the front shell 114 which, consequently, are portions of co-axial cones having their apices on the spinner axis. This conical shape, however, prevents the use of bolts of the type 61 of Figs. 3 and 4. Therefore, in the modified structure, the headed bolts 161 are inserted from the front with their respective axes normal to the conical flange faces, and anchor nuts 167 which may be of conventional type and for this reason do not require further explanation are secured to the rear side of flange 121 by means of rivets 168. Furthermore, the faces of the anchor nut 167, of the

ferrules 163 and 164 and of the washer 166 which are in engagement with the surfaces of the flanges 121, 129 and 133 are curved according to their conical shape. Accordingly, the bolt connection of the bulkhead and the flange of the rear shell illustrated in Fig. 3 would have to be modified, as it will be understood without additional description in view of the foregoing.

The spinner according to the invention is assembled in the following manner: First, the shell 15 is slipped from the rear over the propeller hub with the blades 41 engaging in the recesses 40 and the bottom 16 is fixed to the hub flange 12 by means of bolts 19, the nuts of which can be reached from the front through the wide opening left by flange 21. When this is done, the remaining job of assembling the spinner can be accomplished by working from the front of the hub. The covers 45 are inserted between the flanges 47 of the recess stiffeners 42 and secured by means of the screws 48. Then, the mounting ring 22 is bolted to flange 13. Now, the bulkhead 27 with washer 58 and ferrules 59 and 63 in proper position can be inserted by shifting ring 37 on the cylindrical portion of 26 and by introducing the bolts 50 and 61 into the said ferrules. The tightening of nuts 56 completes the assembling of the rear shell 15. In order to assemble the front shell 14, the ferrules 64 and washers 66 are applied to the holes 65 of flange 33, and the shell 14 is then put on the restricted portion at 20 of shell 15 whereby the nuts 56 enter the holes 60 and the threaded portions of the bolts 61 pass through the ferrules 64. Thereafter, the nuts 67 can be applied to bolts 61 and tightened with the aid of a tool introduced into the interior of the shell through the openings 72. When, finally, the trap doors 76 are closed by releasing the detent springs 91 the spinner assembly is completed. Hence, in order to remove and to restore the front shell 14 when inspection of the control mechanism 11 is required it is only necessary to turn the nuts 67 off and on by reaching through the trap door openings 72. No other part, especially no part in the rear of the propeller hub, need be manipulated for that purpose. Even the interior of the rear shell 15 is accessible from the front side after the removal of the bulkhead 27.

In the case of the modification according to Fig. 7 the sequence of operations is similar to that hereinbefore described with the difference only that bolts 161 are screwed into anchor nuts where in the first described case loose nuts are applied to anchored bolts.

It will be apparent to those skilled in the art that many alterations and modifications of the structure described and illustrated by way of example are possible within the spirit of my invention which shall be limited, therefore, only by the scope of the appended claims.

I claim:

1. A propeller spinner comprising a front shell and a rear shell, said rear shell including an interior bottom with a central opening for attachment to the rear of a propeller hub, and including also a set-off front end with an interior front flange, the rear end of said front shell overlapping said set-off front end of said rear shell, another flange interiorly of said front shell and connected therewith, a bulkhead with a cylindrical center portion for sliding engagement with said hub, a first set of screws securing said bulkhead to said front flange, a second set of screws securing said other flange to both said

front flange and said bulkhead, and trap door provided openings in said front shell forward of and in registry with the screws of said second set respectively.

2. A propeller spinner comprising a front shell and a rear shell, said shells fitting together so as to form a continuously curved surface, said rear shell including a bottom attachable to the rear of a propeller hub, a first flange interiorly of the front end of said rear shell and a bulkhead having a second flange facing said first flange, said front shell including a third flange interiorly of its rear end and facing said second flange, said three flanges being shaped as zones of cones arranged inside each other and having their apices on the spinner axis in front of the cone bases respectively, anchor nuts secured to the rear sides of said first flange, headed screw bolts penetrating said flanges and being screwed into said anchor nuts respectively from the front, the

bolt axes being directed substantially normal to the flange surfaces, and trap doors in said front shell to make the bolt heads accessible from the front side.

3. A propeller spinner comprising a front shell and a rear shell, said shells fitting together so as to form a continuously curved surface, means in connection with said rear shell to secure it to a propeller hub, a plurality of releasable means interiorly of said shells to secure said shells to each other, a trap door coordinate to each one of said releasable means in said front shell so as to make said releasable means accessible, a spring-provided hinge for each trap door, said hinge being attached to the inside of said front shell, and a detent to hold said door open against the restraint of said spring, said detent being accessible through the opening in the front shell to remove it from catching position.

HENRY G. JUNGER.
